(57) **CLAIM**

The ornamental design for a clip for securing articles to the edges of household surfaces, as shown and described.

DESCRIPTION

FIG. 1 is a perspective view of the ornamental design of the clip for securing articles to the edges of household surfaces of the present invention;

FIG. 2 is a rear view of the clip for securing articles to the edges of household surfaces of the present invention;

FIG. 3 is a side view of the clip for securing articles to the edges of household surfaces of the present invention;

FIG. 4 is a front view of the clip for securing articles to the edges of household surfaces of the present invention;

FIG. 5 is a top view of the clip for securing articles to the edges of household surfaces of the present invention; and,

FIG. 6 is a bottom view of the clip for securing articles to the edges of household surfaces of the present invention.

FIG. 1 includes broken lines showing the environment and do not form a part of the design of the claimed invention.
